UNITED STATES PATENT OFFICE.

JOSEPH R. DUMONT, OF KANSAS CITY, MISSOURI, ASSIGNOR TO MAUDE FRANCES DUMONT, OF KANSAS CITY, MISSOURI.

COIN-ACTUATED LOCK.

Application filed January 15, 1923. Serial No. 612,636.

To all whom it may concern:

Be it known that I, JOSEPH R. DUMONT, a citizen of the United States, residing at Kansas City, in the county of Jackson and State of Missouri, have invented certain new and useful Improvements in Coin-Actuated Locks; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to locks and particularly to a lock which normally can be operated only from the outside and only upon the insertion of a coin, check or token of determined value. The lock is so constructed, 20 however, that it may be unlocked from the inside after the coin, check or token has been introduced by the turning of the knob from the inside. This operation causes the lock to be "reset" to re-establish the coin-actuated mechanism ready to function upon the introduction of another check, coin or token.

There is also means whereby an attendant can operate the lock from the outside without inserting a token and there is additional means whereby the lock can be operated from the outside by using a special key.

The lock is especially designed for application to booths in comfort stations and primarily belongs to the general class known as toilet door locks. It embraces means for automatically locking the bolt against actuation from the outside when the door is closed but not against operation from the inside. It embraces a counter or registering mechanism which functions only when a token or coin of proper denomination passes through the mechanism, the counter or registering mechanism being such that it will not function when the custodian's or attendant's key is used, nor will it function when the other key known as a manager's key is used.

It also includes a signal to indicate whether or not the booth is occupied and it contemplates other novel features, all of which will be specifically referred to hereinafter, reference being had to the accompanying drawings, in which

Fig. 1 is a perspective view of a lock constructed in accordance with my invention,

the face plate for the coin receptacle being 55 removed and the custodian's key being shown in position to be introduced through the outside knob.

Fig. 2 is a horizontal, cross sectional view through the lock and the outside and inside 60 knobs.

Fig. 3 is a vertical, cross sectional view through the housing, the mechanism being shown in front elevation.

Fig. 4 is a similar view of the mechanism 65 shown in rear elevation.

Fig. 5 is an elevational view of the signal arm, a detent and a latch bar.

Fig. 6 is a perspective view of the mechanism actuated by the manager's key. 70

Fig. 7 is a vertical, longitudinal, sectional view through the complete lock.

Fig. 8 is a fragmentary, perspective view of the inside spindle escutcheon.

Fig. 9 is a perspective view of the bolt and the throw fingers operated by the outside and inside knobs. 75

Fig. 10 is a detail perspective view of the tumbler.

Fig. 11 is an elevational view of the bolt, 80 the tumbler, the throw fingers and the mechanism operated by the manager's key viewed from the front, showing the bolt projected.

Fig. 12 is a similar view of the bolt, the tumbler, the coin release showing the bolt 85 retracted.

Fig. 13 is an elevational view of part of the bolt, the throw fingers, the coin release and the coin chute, the coin release being 90 shown in releasing position.

Fig. 14 is a like view showing the coin release supporting the coin or token, the coin chute being shown in section.

The lock case or housing is shown as a vertically elongated shell 1, having at its upper end two slots 2 and 3, the first being a signal slot and the second a coin slot. In the front wall of the case is an opening 4, adapted to be closed by a cover plate or door 5, having at its upper edge a projecting offset lip or flange 6, to engage the upper edge of the opening 4, the lower end of the cover plate being fastened by a locking lug 7 engaging a slot 8 in the keeper plate 9, fastened to the interior of the case. The locking lug is adapted to be controlled by a lock 10 of appropriate construction, the lock being operated by a key 11. When the cover plate is

removed, access can be had to the bottom of the case to remove the coins which have been deposited therein.

The main lock carrying frame is shown as 5 consisting of three substantially parallel plates designated 12, 13 and 14, arranged from the front to the back in the order named. The intermediate plate 13 supports the remaining plates and the entire frame is 10 secured in an appropriate manner within the case. The plate 13 carries a coin chute 15, the inlet end 16 of which registers with the slot 3 so that the coin, check or token, hereinafter referred to as a coin, can be introduced 15 into the coin chute so that it may pass through to be intercepted by the coin-actuated mechanism.

Below the coin chute are two coin detent levers 17 and 18, pivoted to the plate 13. 20 The toe 19 of the lever 17 and the curved face 20 of the lever 18 are in spaced relation but the space between them will normally be such as to prevent the passage of the coin until the bolt is withdrawn. The 25 toe 19 of the lever 17 is normally in the position shown in Fig. 13. When the coin drops from the chute 15, it will contact with the toe of the lever 17 and cause it to move downwardly to the position shown in Fig. 30 14 so that the coin will at first be held in the position shown in Fig. 14. As the toe of the lever 17 moves downwardly, its heel 21 will be raised, carrying with it a pivoted register-actuating dog 22, the toe 23 of 35 which may move into position to be engaged by the longitudinally movable bolt 24, which is to be actuated by mechanism to be hereinafter described.

The heel 25 of the dog 22 will be in position 40 to contact with a lateral finger 26 on the spindle 27 of a register 28 so that when the bolt is withdrawn and the dog 22 is rocked by contact of the end of the bolt with the toe 23, the finger 26 will be swung 45 about the axis of the spindle 27 and register one coin. The construction of the register per se constitutes no part of the present invention; suffice it to say that there is a return spring in the case of the register 28 to return the finger to normal position after 50 it has been actuated.

The movement of the bolt to unlocking position will throw the coin detent or lever 18 about its pivot 29 because the heel 30 of 55 the lever 18 engages a notch 31 in the bolt. Therefore, the withdrawal of the bolt will be effective in widening the distance between the toes 19 and 20, permitting the coin, check or token designated 32 to drop into the bottom of the case 1.

As soon as the weight of the coin 32 is 60 taken off the toe of the lever 17, the lever will re-assume the position shown in Fig. 13. The bolt 24 is urged outwardly into keeper-engaging position by a spring 33

which is carried by the plate 13. The bolt 24 can be retracted by either of two throw levers or fingers 34 or 35. The finger 34 is carried by the spindle 36 integral with the outside knob 27. The spindle 36 has a central longitudinal opening or key-passage-way 38 extending entirely through it for the introduction of the custodian's key 39, as will be explained more in detail hereinafter.

When the spindle 36 is turned, the throw 75 finger 34 is turned so that it will press against the bolt-actuating lever 40, pivoted to one face of the plate 13 by a pivot 41, which extends through the plate 13 and supports a lever 42, similar to the lever 40, the 80 lever 42 being actuated, however, by the throw lever 35 on the hub 43 supported in the plate 13 and adapted to be operated only by the inside knob 44 on the inside spindle 45 or by the key 39, which is adapted to 85 extend through the opening 38 and engage the cross pin 46, carried by the hub. The outside knob cannot be turned, however, until certain releasing devices are operated; that is, when the coin has passed through 90 the slot 15 and been deposited on the toes 19 and 20 of the levers 17 and 18 so that the heel 21 of the lever 17 is raised. The lever 17 raises a latch bar 47 having a lip 48 extending through the opening 49 in the plate 95 12. The lip 48 will normally lie against the offset or shoulder 50 on the lever 40 (see Fig. 11) so that unless a coin is deposited, the turning of the knob cannot rock the 100 rocking finger 34 because the lateral movement of the lower portion of the lever 40 will be opposed by the lip. When the coin is deposited, however, so as to depress the toe 19, the latch bar 47 will be raised high 105 enough to permit the lip 48 to move off the shoulder to the position shown in Fig. 12. Then the spindle can be turned to rock the finger 34 and thereby rock the lever 40, it being seen by reference to Fig. 12 that the 110 lever 40 has a semi-circular cut-out portion 51, which snugly hugs the hub for the finger 34. Therefore, when the coin has depressed the toe 19 of the lever 17 and the lip 48 has moved to the position shown in 115 Fig. 12, it is obvious that the rocking finger 34 can actuate the rocking lever 40, withdrawing the bolt which is supported by a lug 52 carried by the plate 13 and projecting through the slot 53 in the bolt. As the bolt 120 is retracted by reason of the fact that the lower end of the rocking lever 40 engages the lateral extension or shoulder 54 on the end of the bolt 24, a signal operating finger 55 will be swung so that its projecting end 125 53 will swing the arm 57 about the pivot 58 on plate 12.

Since the arm 57 carries a signal segment or blade 59, on which indicia is placed, the blade 59 in its original position will indicate that the booth is vacant. Then when the 130

arm 55 moves the arm 57 over to the position shown in Fig. 5, the indicia on the blade 59 will indicate through the slot 2 that the booth is occupied. The arm 57 is held against the plate 12 by a struck-out projection 60, which bears against the face of the plate 12 opposite to that on which the arm 57 is positioned.

It has been stated before that the latch bar 47 moves longitudinally in an upward direction when the coin is deposited so that the lip 48 will move away from the shoulder 50. The latch bar 47 is provided with a notch or shoulder 61, which is adapted to be engaged by the detent or dog 62, having a curved heel portion 63. The dog 62 is pivoted to the plate 12 and its toe portion is moved into engagement with the notch 61 by the curved lower end 64 of the arm 55 when the bolt is retracted, that is, when the spindle 36 is turned. Therefore, the lip 48 will be held out of engagement with the shoulder 50 when the signal indicates that the booth is occupied. When the signal arm 57 is moved back to its normal position, however, the heel portion 63 will ride under the shoulder 65 (see Fig. 5) of the arm 57, withdrawing the toe of the dog 62 out of the notch and allowing the latch bar 47 to drop back into the position shown in Fig. 11. The arm 55 only moves the arm 57 into position to indicate that the booth is occupied.

To restore the arm 57 and the blade 59 to position, another mechanism is employed, which actuates the arm 66, pivoted at 67 to the plate 14, the arm 66 being fastened to the signal at its upper end. The arm 66 is pulled back to position to indicate that the booth is unoccupied by a link 68 attached to the pin 69 on the lower end of the lever 42 when the bolt is retracted due to the turning of the inner knob 44 to rotate the spindle 45, this action occurring when the occupant is leaving the booth. The functioning of the inner knob will be more clearly described further on.

When the occupant is about to leave the booth, he will turn the knob 44; the spindle 45 then engages the hub 43 by means of a flat tooth or projection 70 on its end, which is received in a slot 71 in the hub. The tooth 70 is maintained in position by the escutcheon 72, which is fastened to the door and which has a recess 73 receiving a slotted rocking plate 74 engaging a circumferential groove 75 in the spindle 45. Therefore, when the escutcheon is fastened to the door, longitudinal movement of the spindle 45 will be prevented but it may obviously turn in the escutcheon to turn the hub 43 whereby the throw lever 35 is actuated to impart swinging movement to the lever 42 to retract the bolt.

The inner knob can be turned to retract

the bolt through the hub 43, the throw lever 35 and the lever 42 without the insertion of a coin and without operating the registering mechanism but when the knob is turned, the signal is re-set and in re-setting the signal, the lever 57 is swung back to the position shown in Fig. 3, restoring the lever 55 to the position shown in Fig. 3 and restoring the detent or dog 62 to its position; the latter operation resulting from the fact that the cam 65 rides up on the heel of the detent 62 and throws the toe out of engagement with the notch 61. This permits the latch levers 47 to drop back to the position shown in Fig. 3. The parts of the lock are now restored to normal position so that they can again be operated from the outside upon the insertion of a coin.

Means is provided for preventing the operation of the bolt from the outside unless a coin is introduced into the slot 15. This means is in the form of a detent which I will term a secondary bolt-actuated tumbler. The element is designated 76 and is pivoted to the lock frame at 77. The detent has a hooked end 78 adapted to ride behind the end of the bolt 24 when the lower end is moved downward under the action of the spring 79 anchored at 80 to the frame and having a free end 81 bearing against the under side of the detent. The end 78 is maintained out of engagement with the end of the bolt 24 by a pin 82 on the spring-actuated secondary bolt 83, normally urged outwardly by the spring 84, the outward movement being limited by the stop pin 85. The end of the bolt 83 is beveled, as at 86, so that when the door is closed, the bolt will be projected inwardly, moving the pin 82 out of engagement with the tooth 87 so that the tooth will move downwardly under the action of the spring 79, allowing the hook 78 to move back of the end of the bolt 24. Therefore, the lock cannot be picked by hairpins, shoe buttoners and similar unauthorized devices.

The bolt 24 can be retracted only when the knob 37 or the knob 44 is turned. The knob 37 cannot be turned, of course, unless the coin-actuated mechanism is operated and the knob 44 can be turned only by an occupant of the booth. When either knob is turned in an authorized manner, one of the fingers or wards 84 or 85 will ride on the curved or arcuate-shaped flange 88 so as to depress the hook end 78 out of engagement with the bolt, for otherwise the bolt could not be retracted. It is to be understood, of course, that the end of the bolt 83 does not enter a recess or a keeper in the door frame but merely bears against the face of the door frame. It is in no sense a locking bolt but merely a safety device. It will, therefore, be apparent that the lock can be opened by the public only upon the turning of the knob 130

37 in the first instance and subsequently, the turning of the knob 44 and that the knob 37 cannot be turned until a coin of proper denomination or value is introduced into the 5 slot 16.

It sometimes happens that the custodian finds it necessary to have access to the booth and obviously it is not desired that the registering mechanism operate when the door is 10 opened by the custodian. In order to take care of this, I have provided the key 39 with the slit end 89, which may be introduced through the opening 38 to engage the pin 46 so that the hub 43 can be turned 15 from the outside in the same manner that it can be turned from the inside. When the hub 43 is turned through the medium of the key 39, it will cause the parts of the lock to function in the same manner as described with respect to the turning of the 20 knob 44. It is recommended that the key 39 be made relatively large and of considerable length so that the use of duplicates by the public would be inconvenient because 25 otherwise, the custodian might have duplicate keys made for promiscuous distribution.

It is desirable to provide means for operating the lock by authorized persons without the introduction of a coin. For example, 30 the executive force of an institution, hotel or the like may desire to have access to the booth without paying a fee. To this end I have provided what I am pleased to call a 35 manager's-key-operated mechanism, which will release the bolt-retaining mechanism without the introduction of a coin or without disturbing the coin-actuated elements. The mechanism for permitting the operation 40 of the lock without a coin or without the key 39 is best shown in Figs. 3, 4, 6 and 11.

A yoke lever 90 is pivoted to the frame at 91; the yoke lever having a depending lateral arm 92 which may engage the pin 93 which connects the lever 17 to the latch bar 47. The yoke lever 90 has a transversely projecting arm 94 which may be engaged by an eccentric pin 95 on the end of a lock 96 operated by the key 97 (Figs. 1 and 6), the 50 lever being held in functional position by a spring 98 (Fig. 6).

When the manager's key 97 is turned in the lock 96, the pin 95 will engage the arm 94, raising the lever 90 and since the arms 55 92 and 94 provide a yoke-shaped end for the lever 90, through which the pin 93 extends, it is obvious that the raising of the free end of the lever 90 will cause the arm 92 to raise the pin 93 and impart an upward movement 60 to the latch bar 47. The latch bar 47 will, therefore, move enough to raise the latch 48 out of engagement with the shoulder 50 of the throw lever 40. Consequently, the spindle 36 can be turned, causing the finger 34 65 to be turned so that it will ride on the flange

88 to throw the detent out of engagement with the bolt 24 and at the same time cause the lever 40 to retract the bolt. Therefore, the person using the manager's key may have access to the booth without introducing 70 a coin.

Of course, in raising the pin 93, the lever 22 will be raised but it will not be raised high enough to permit the bolt to engage the toe 23. Therefore, the lever 22 will not 75 be rocked and since it will not be rocked, the registering mechanism will not be operated. It will, therefore, be apparent that when the custodian or when the person in possession 80 of the manager's key operates the lock, the registering mechanism will not function. The registering mechanism will function only upon the introduction of an authorized coin and upon operation of the lock in the prescribed way.

The levers 40 and 42 are urged to neutral position by the springs 41' and 42' which are fastened to the upper ends of the levers 40 and 42 and to the side of the case. The location of the springs 41' and 42', however, may be changed without materially affecting the invention and in order to permit the coin to pass from the slot 3 into the coin guiding slot 15, I provide a slot 59' in the 90 signal segment or guard 59.

From the foregoing it will be apparent that the lock can be conveniently operated to permit access to a booth upon the introduction of a coin of proper denomination, that the custodian may have access to the 100 booth by use of a special key without registering the fact that the lock is functioned, that the executive force by use of a special key may also operate the lock without registering, and that the booth can be opened 105 from the inside without registering the mechanism, and the fact that the lock is worked from the inside will restore the operating mechanism to a normal functional position; that is, to a position where it can operate only upon the introduction of a coin. This is an important feature of the invention because it compels the persons who use the booth to reset the lock in the act of 110 making their exit from the booth.

What I claim and desire to secure by Letters-Patent is:

1. A coin-operated lock including a casing, independently rotatable door knob spindles journaled in the casing and accessible from opposite sides thereof, a lock mechanism associated with the spindles comprising a pivotally mounted swinging member for each of said spindles, means on each spindle for actuating its swinging member, a locking bolt retractable by either of said swinging members, means for guiding coins through the casing, a trip in the path traversed by the coins, a latch bar connected to the trip normally resisting movement of 120 125 130

but one of said swinging members but rendered ineffective to resist movement of said member upon actuation of the trip by a coin, and a detent operatively connected to the bolt to support the coin in functional position and to release the coin when the bolt is actuated.

2. A coin-operated lock including a casing, independently rotatable inner and outer door knob spindles journaled in the casing and accessible from opposite sides thereof, a throw lever fixed to each spindle, swinging members individually operable by respective throw levers, a locking bolt retractable by either swinging member, a latch bar normally resisting movement of the swinging member for the outer door knob spindle, a trip operably connected with the latch bar, means for guiding a coin to contact with the trip whereby weight of a coin may shift the latch bar to release the swinging member for the outer door knob spindle, and a detent operatively connected to the bolt to support the coin in functional position and to release the coin when the bolt is actuated.

3. A coin-operated lock including a casing, independently rotatable inner and outer door knob spindles journaled in the casing and accessible from opposite sides thereof, a throw lever fixed to each spindle, pivotally mounted and spring retracted swinging members individually operable by respective throw levers, a locking bolt retractable by either swinging member, a latch bar normally resisting movement of the swinging member for the outer door knob spindle, a trip operably connected with the latch bar, means for guiding a coin to contact with the trip whereby weight of a coin may shift the latch bar to release the swinging member for the outer door knob spindle, and a detent operatively connected to the bolt to support the coin in functional position and to release the coin when the bolt is actuated.

4. A coin-operated lock including a casing, independently rotatable door knob spindles journaled in the casing accessible from opposite sides thereof, a lock mechanism associated with the spindles comprising swinging members independently movable in response to turning movement of respective spindles, a locking bolt retractable by either of said swinging members, means for guiding coins through the casing, a trip in the path traversed by the coins, a lever on the trip moved into the path of movement of the locking bolt by the weight of the coin on the trip, a register mechanism actuated by the lever when the bolt is retracted by turning one of the spindles only, and a latch bar carried by the trip normally resisting turning movement of one of the swinging members but moved out of

functional position when the trip is actuated by the coin, and a detent operatively connected to the bolt to support the coin in functional position and to release the coin when the bolt is actuated.

5. A coin-operated lock mechanism including a casing, independently rotatable door knob spindles journaled in the casing and accessible from opposite sides thereof, a lock mechanism associated with the spindles comprising swinging members independently movable in response to turning movements of respective spindles, a locking bolt retractable by either of said swinging members, means for guiding coins through the casing, a trip in the path traversed by the coins, a latch bar connected to the trip normally resisting movement of one of the swinging members but movable out of such position when the trip is actuated by a coin, a detent operatively connected to the bolt to support the coin in functional position and to release the coin when the bolt is actuated, a lever carried by the trip having an end movable in the path of movement of the lock bolt when the latch bar is in non-functional position, and a registering mechanism engageable by the lever for operating the registering mechanism when the lock bolt is retracted.

6. A coin-operated lock including a casing, independently rotatable door knob spindles journaled in the casing and accessible from opposite sides thereof, a lock mechanism associated with the spindles comprising swinging members independently movable in response to turning movement of respective spindles, a locking bolt retractable by said swinging members, a latch bar normally resisting movement of one of the swinging members, a trip connected with the latch bar having a member engageable by a coin to shift the latch bar, a detent operatively connected to the bolt to support the coin in functional position and to release the coin when the bolt is actuated, a register operating member on the trip engageable by the bolt when the trip is coin actuated, a register operable by said member, and a key-actuated device operable on the trip to shift the latch bar, movement of the latch bar by the key-operated device being to a less extent than movement of the bar by the trip to prevent engagement of the register-operating lever by the bolt.

7. A coin-operated lock including a casing, independently rotatable door knob spindles journaled in the casing accessible from opposite sides thereof, a lock mechanism associated with the spindles comprising swinging members independently movable in response to turning movements of respective spindles, a locking bolt retractable by either of said swinging members, means for guiding coins through the casing,

- a trip in the path traversed by the coins, a latch bar connected to the trip normally resisting movements of one of the swinging members but rendered ineffective upon the 5 insertion of a coin in the casing, a detent movable into engagement with the latch bar upon turning one of the spindles after the coin has been inserted whereby the latch bar will be positively held in non-functional 10 position, a detent operatively connected to the bolt to support the coin in functional position and to release the coin when the bolt is actuated, a signal arm movable in response to the turning movement of the 15 spindle which has actuated the detent, means actuated in response to turning movement of the other spindle for restoring the signal arm to its original position, and means on the signal arm for moving the detent out of engagement with the latch bar to permit the latch bar to reassume its original 20 position.
8. A coin-operated lock including a casing, independently rotatable door knob spindles journaled in the casing accessible from opposite sides thereof, a lock mechanism associated with the spindles comprising swinging members independently movable in response to turning movements of respective spindles, a locking bolt retractable by either of said swinging members, 25 means for guiding coins through the casing, a trip in the path traversed by the coins, a latch bar connected to the trip normally resisting movement of one of the swinging members but movable out of functional position when the trip is actuated by a coin, a detent for holding the latch bar in non-functional position, means for actuating the detent upon turning one of the spindles, a detent operatively connected to the 30 bolt to support the coin in functional position and to release the coin when the bolt is actuated, a signal arm movable in one direction by the detent-actuating means, the signal arm having a part for engaging with the detent to throw it out of contact with the latch bar when the signal arm is restored to its original position, and means actuated by the other spindle for restoring the signal arm to its original position.
- 40

means movable in response to the key-actuated device to permit the latch bar to be moved into non-functional position so that 45 the lock can be operated without introducing the coin into the casing, said means comprising a lever having a yoke-shaped end for lifting the latch bar, the yoke-shaped lever being engageable by an eccentric pin on the key-actuated device.

9. A coin-operated lock including a casing, independently rotatable door knob spindles journaled in the casing accessible from opposite sides thereof, a lock mechanism associated with the spindles comprising swinging members independently movable in response to turning movements of respective spindles, a locking bolt retractable by either of said swinging members, 50 means for guiding coins through the casing, a trip in the path traversed by the coins, a latch bar connected to the trip normally resisting movement of one of the swinging members but movable out of functional position when the trip is actuated by a coin, a detent for holding the latch bar in non-functional position, means for actuating the detent upon turning one of the spindles, a detent operatively connected to the 55 bolt to support the coin in functional position and to release the coin when the bolt is actuated, a signal arm movable in one direction by the detent-actuating means, the signal arm having a part for engaging with the detent to throw it out of contact with the latch bar when the signal arm is restored to its original position, and means actuated by the other spindle for restoring the signal arm to its original position.

80 In testimony whereof I affix my signature.

JOSEPH R. DUMONT.
